DESIGN FOR A FOOTREST FOR A BEACH CHAIR OR SIMILAR ARTICLE

Andrew J. McGann, New York, and Albert
Beeskow, Brooklyn, N. Y., assignors to Tropical
Chair Co., Inc., New York, N. Y., a corporation
of New York

Application April 16, 1940, Serial No. 91,706

Term of patent 7 years

To all whom it may concern:

Be it known that Andrew J. McGann and Albert Beeskow, citizens of the United States and resident of New York city, in the county of the Bronx, State of New York, and Brooklyn, in the county of Kings, State of New York, respectively, have invented a new, original, and ornamental Design for a Footrest for a Beach Chair or Similar Article, of which the following is a specification, reference being had to the accompanying drawing, forming part thereof, and in which the figure is a perspective view of a footrest for a beach chair, embodying our new design.

The characteristic feature of the footrest is shown in full lines and comprises the longitudinal curvature of both the side members and slats, said side members and slats diverging rearwardly, the side members being of substantially greater length than the slats.

We claim:

The ornamental design for a footrest for a beach chair or similar article, substantially as shown and described.

ANDREW J. McGANN.
ALBERT BEESKOW.
